DENTAL POWDER DISPENSER

Oril M. Polkingharn, Cheyenne, Wyo.

Application January 12, 1939, Serial No. 250,608

5 Claims. (CL 221—62)

This invention relates to improvements in dispensing devices, especially of the type for dispensing dentifrices. A more particular purpose of the invention is to enable the dispensation of dental powders in a clean, orderly and entirely non-wasteful manner.

The popularity of dental powder depends in some measure on the emphasis laid on its use by advertisers who attribute its value largely to the fact that professional dentists use it as a cleansing agent. Regardless of the merits of a powder cleanser the fact remains that it is preferred by a large number of persons who, in the majority of instances, shake a little of the powder into the palm of one hand whence it is taken up by the wet bristles of a tooth brush.

This mode of applying the powder to the brush is far more economical than attempting to sprinkle the powder directly on the bristles. But in each case there is a considerable waste of powder which is sought to be eliminated by the instant invention, the objects of which are as follows:

First, to provide a dispenser for dental powder which enables the application of a given quantity of powder to the bristles of a tooth brush in such a manner as not to waste any of it.

Second, to provide a dispenser which enables the application of a measured quantity of tooth powder in ribbon form.

Third, to provide a powder dispenser having the foregoing characteristics, which is readily applicable to conventional types of containers, and which is capable of being so cheaply constructed as to warrant the throwing away of the empty container, thus avoiding having to shift or transfer the dispensing device from one container to another.

Other objects and advantages will appear in the following specification, reference being had to the accompanying drawing in which:

Figure 1 is a perspective view illustrating the manner of use of the improved powder dispenser.

Figure 2 is a perspective view of the dispensing device showing the plunger all the way back at the beginning of a stroke.

Figure 3 is a cross section taken on the line 3—3 of Fig. 2 showing the plunger in the same position.

Figure 4 is a cross section taken on the line 4—4 of Fig. 3.

Figure 5 is a section similar to Fig. 3, but illustrating the plunger at the other extremity of its stroke.

Figure 6 is a perspective view of the plunger barrel.

In carrying out the invention the container 1 is provided with a top 2 which has a longitudinal slot 3 or equivalent opening. The container 1 is intended to be filled with tooth powder, but it may contain any other equivalent substance which is capable of dispensation in the manner presently described.

The slot 3 is covered with a barrel 4. The latter consists of an appropriately stamped metal piece, which comprises a top 5, sides 6, bottom sections 7 and end sections 8. The sections 8 constitute a closure for one end of the barrel, the other end being left clear to provide a discharge opening 9. Said opening is situated slightly beyond the end of the top 2 because of the projection of the barrel at 4a. This projection slightly facilitates the laying on of the powder ribbon inasmuch as the position of the opening 9 can be kept in view.

Tabs 10 are included in the stamping, these being bent over the end sections 8 to secure the latter. Flanges 11 are bent down from the confronting margins of the sections 7 (Fig. 6) and after these flanges are inserted through the slot 3 they are upset at 12 (Fig. 4) to securely fasten the barrel 4 to the top 2. The flanges 11 thus form the main part of a powder inlet 12a from the container into the barrel.

It is to be observed that the barrel 4 is rectangular in cross section. The result is the discharge of a cross sectionally rectangular ribbon 13 of tooth powder (Fig. 1). It is also to be observed that the barrel is perfectly smooth on the inside, in other words, there is no obstruction whatsoever to the free back and forth passage of the plunger 14. This plunger comprises a strip of metal which is sufficiently rigid to prevent undue bending when it is pushed back and forth. The part designated 14 is actually the head which discharges the powder ribbon. It is slightly offset at 15 to provide a friction surface against the inside of the top 5 of sufficiently large expanse to prevent any free movement of the plunger when not in use.

The plunger head is part of a stem 16 which is slidable in and projects from a slit 17 in the end closure 8. The stem 16 terminates in a finger-piece 18 by which the plunger is capable of being pushed (Fig. 1). The finger-piece acts as a stop (Fig. 5) to limit the pushing in of the plunger head.

The operation of the invention is readily understood. In its initial position the stem 16 is made to serve as a closer for the powder opening 12a (Fig. 5). This function is, obviously, per-

formed by pushing the plunger stem all the way in. The plunger head 14 is then substantially flush with the margin of the discharge opening 9, thus the plunger not only prevents powder from being inadvertently shaken into the barrel, but it also prevents the entrance of foreign matter into the barrel.

Upon desiring to dispense a quantity of the powder, the finger of one hand is held lightly over the discharge opening 9. The container 1 is then turned upside down so as to load the barrel 4, this being accomplished by the gravitation of the powder into the barrel. The finger tip over the opening 9 prevents the powder from prematurely sifting out.

The finger-piece 18 is now pushed upon (arrow a, Fig. 1), moving the plunger head 14 toward the discharge opening 9. Tooth powder is commonly reduced to extremely fine particles, and being such it is easily possible for the load of powder to be compacted tightly enough in the barrel 4 by the motion of the plunger head 14 to make it take the shape of the cross sectionally rectangular ribbon 13. As the finger-piece 18 is pushed upon the entire container 1 is moved across the tooth brush 19 (arrow b, Fig. 1) laying the powder ribbon 13 upon the extremities of the bristles. This ribbon takes the form of an unbroken stick of powder, the whole operation being neatly and quickly accomplished.

The preferred cross sectional shape of the ribbon is rectangular. This prevents any chance of its rolling off of the brush should the latter be tilted slightly. It will be understood from the foregoing statements that the entire dispensing device is made very cheaply. Actually it consists only of the barrel and the plunger. No solder or rivets are required in completing the assemblage. Consequently the entire container can be thrown away when emptied.

The barrel 4 is of such proportions that one operation dispenses enough powder for one brushing of the teeth. The same operation that causes the dispensation of the powder ribbon 13 also serves to close the container because then the head 14 will have come flush with the margin of the opening 9 (Fig. 5) and the stem 16 will have become superimposed upon the powder inlet 12a.

I claim:

50. 1. A dispenser fundamentally intended for loose powder comprising a temporary and replaceable powder container having an opening,

powder receiving means temporarily attached to the container in communication with the opening and in turn having a discharge opening, and plunger means freely slideable back and forth in the receiver means by manual effort to slightly compact a load of powder upon being slid in the receiver in one direction after the admission of a charge of powder from the container thus to eject the powder from the discharge opening in ribbon form onto a contiguous support.

2. A dispenser comprising a temporary and replaceable powder container having an opening, repeatedly usable receiver means attached to the container over said opening to be in communication therewith, said receiver means having a discharge opening and an elongated powder inlet providing for a substantial filling of said receiver means by appropriately tilting the container, and plunger means backing the charge of powder thus obtained and being operable in the receiver means for the ejection of the powder charge at said discharge opening in ribbon form.

3. A dispenser comprising a powder container having an opening, a barrel having means securing it to said container at said opening and at the same time defining a powder inlet, said barrel having a discharge opening unobstructed from the outside, and a plunger operable back and forth in the barrel by finger pressure, including a head and stem respectively adapted to occupy and close the discharge opening and cover the powder inlet when in one position.

4. In a dispenser, a barrel adapted to receive a load of powder, having a discharge opening at one end and a slit at the other end, a plunger having a head operable in the barrel and a stem slideable in the slit, and an offset on the head providing an expanse in contact with the interior of the barrel to increase resistance.

5. In a dispenser, a container which is adapted to be manipulated by the hand of a user, a top attached to said container and having a powder opening, a barrel on the top and communicating with the container through said opening, said barrel having a discharge opening projecting beyond the top to insure the visibility of said opening when and as the container is handled as stated, and a plunger head operable in the barrel by finger pressure, being movable to a point substantially flush with the discharge opening for the complete discharge of a ribbon of powder.
